METAL BUILDING CONSTRUCTION

William C. Lea, Los Angeles, Calif.

Application August 31, 1933, Serial No. 687,614

4 Claims. (Cl. 189—1)

This invention has to do in a general way with the art of building and is more particularly related to improvements in the framework of buildings whereby they are rendered fire proof, 5 earthquake proof and are immune to the natural disintegration brought about by decay, termites, etc., such as occur in wooden structures.

It is one object of this invention to produce means for constructing metal buildings which 10 are of light weight and can be easily handled.

It is a further object of this invention to provide means of the class described which can be economically manufactured and from which the framework of a building can be quickly and 15 easily fabricated or erected with either skilled or unskilled labor.

It is a still further object of this invention to provide means of the class described wherein the individual elements are of standard shape 20 and are provided with regularly spaced attaching means whereby they can be cut to specifications, at the point of manufacture, and can be assembled or erected by means of a screw-driver, or other suitable tool or tools, depending upon 25 the type of securing means employed.

The general construction of the building material, contemplated by this invention, comprises metal channels which are formed of two or more different widths so that part of the channels can 30 fit within other of the channels. These channel members are provided, both in their web portions and in their flanges, with regularly spaced bolt holes, or fastening holes, such holes being arranged in sets or pairs, the sets or pairs being 35 spaced apart throughout the length of the channels at equal distances. It is, therefore, one feature of the invention that channel members of this nature may be secured together to form a frame, the parallel members of which are 40 spaced apart at any predetermined distance within the increments of length between the sets of bolt holes, or other fastening holes.

It is a further object of this invention to provide channels, of the class described, with bolt 45 holes of novel construction in that they are countersunk so as to interfit whereby the shear stresses in two adjacent members are carried by the countersunk portions in such members rather than the bolt, or other securing means, 50 whereby the members are locked together.

In this invention it is a still further object to provide for use, in combination therewith, a novel bolt and nut construction, the head of the bolt being adapted for reception in the counter-sink, above referred to, and the nut being provided with projecting points or corners which engage the inner surface of the member through which the bolt extends and, through such engagement, is held against turning during the insertion and tightening of the bolt.

It is a still further object of this invention to provide channel members of the class described with a plurality of large uniformly spaced openings formed in the webbed portion of the channel members, such openings providing a wall which is ventilated throughout and also providing convenient means for the placement of pipe or conduit within the wall. In this connection it is another feature of this invention that it is adapted to the construction of a wall, finished 10 on both sides, wherein the pipe or conduit is readily accessible from the outside. This object is attained by virtue of the fact that a covering member, such as a wall board or a base plate, can be readily removed to give access to the interior 15 of the wall itself.

My invention also contemplates a novel type of base plate or base board construction which 20 can be easily and quickly removed for the purpose above referred to.

Another novel feature of this invention resides in the fact that the studding of a wall, of the class described, is employed to form the side jambs of the doors and windows. It is well known, to those familiar with the art, that the 25 door and window frames in conventional building construction are separate units inserted in the framework of the building after it has been erected. The elements of my invention are of a nature such that horizontal braces can be placed 30 between the studdings to form head jambs or sills and stop members or guide members can be placed directly on the portion of the studding between such horizontal braces to form a complete window or door frame.

It is a further object of this invention to provide means, formed in the channel members above referred to, whereby a covering material, such as metal lath and plaster or wall-board, 40 can be easily and quickly mounted on the channel members.

The details in the construction of certain preferred forms of my invention, together with other objects attending its production, can best be understood from the following description 45 of the accompanying drawings, which are chosen for illustrative purposes only, and in which—

Fig. 1 is a fragmentary perspective view, with parts broken away, showing a portion of a building frame embodying certain of the features contemplated by this invention;

Fig. 2 is a partial sectional elevation illustrating the manner in which a sill member is secured to the foundation;

Fig. 3 is a fragmentary perspective view illustrating a preferred form of base plate or base board connection;

Fig. 4 is a fragmentary view, partly broken away, illustrating in detail the construction of a

- Fig. 14 is a plan section showing a preferred form of door jamb construction contemplated by this invention;
- Fig. 15 is a fragmentary plan section similar to Fig. 14 but showing a modified form of trim member which may be used in conjunction with a plastered wall;
- Fig. 16 is a fragmentary perspective view, with parts broken away, showing a preferred form of clip member which may be used in securing wall-board to a frame in the type contemplated by this invention;
- Fig. 17 is a plan section showing a modified form of wall-board retaining strip;
- Fig. 18 illustrates a splice construction which may be used in connection with the channel members contemplated by this invention;
- Fig. 19 is an elevational view showing a modified form of frame construction in which the elements of my invention are adapted for use;
- Fig. 20 is an enlarged elevation illustrating the construction of the end of the roof truss shown in Fig. 19;
- Fig. 21 is an end view of the connection shown in Fig. 20;
- Fig. 22 is an elevation, with parts broken away, illustrating the manner of connecting the brace members in the roof truss shown in Fig. 19;
- Fig. 23 is an enlarged view showing an elevation of the end portion of the floor truss shown in Fig. 19; and
- Fig. 24 is an elevation, with parts broken away, illustrating the manner of connecting the brace members in the said floor truss.
- More particularly describing the invention, as herein illustrated, reference numerals 11 and 11' indicate the corner of a foundation upon which channel members 12 and 12' are positioned with their web surfaces 13 resting on top of the foundation and their flange portions 14 extending upwardly. These channel members 12 and 12' form sills for the building frame and receive the lower ends of upright channel members 15 which constitute the studding for the frame. The studding members 15 are provided with horizontal braces 16 and angle braces 17 and the upper ends of the channels are received in an inverted channel member 18 which forms the plate of the building frame. The plate 18 carries a plurality of ceiling joists 19, which are also channels, having their flanges resting on top of the plate 18. Reference numeral 20 indicates rafters, which are channel members similar to the studding and ceiling joists, such members being secured at their web portions with the webs of the ceiling joists 19. In order that the studding members may be spaced apart in various predetermined increments of length, and, at the same time, be faced in either direction and also to provide a standard construction, in which the braces and other elements may be correspondingly mounted at predetermined points, I form the channel members, contemplated by this invention, with bolt or fastening holes 21 and 21', for example, such bolt holes being arranged in pairs or sets and the sets being spaced apart at equal distances through the length of the unit. Furthermore, in order to provide a wall structure which is ventilated throughout and in which pipe or conduit may be conveniently mounted, I provide the channel members with additional large openings 23 which are also uniformly spaced apart.
- One use of the last mentioned openings 23 is illustrated by the pipe or conduit 24. Another use of the openings 23 resides in the means of connecting the sill channel 12 to the foundation. Such connection is best illustrated in Fig. 2 where the foundation is shown as being provided with a bolt 26 adapted for reception in one of the enlarged openings 23. In securing the sill channel to the foundation a washer 27 is placed over the opening 23 and a nut 28 is screwed onto the bolt to engage the washer. It is to be understood that while I have shown the openings 23 as being rectangular in cross section, that these openings may be made round or any other shape.
- In forming the corner of a building frame, of the type contemplated by this invention, studs 15 are placed in the adjacent ends of both the sill channels. The inner adjacent flanges of these two studs are then connected by means of an angle member or corner clip 30 and the outer flanges of the two channels are connected by means of an outer corner member or corner clip 31. In this connection it is to be understood that all of the members are punched or stamped with the bolt holes in the same spaced relation so that in a corner construction, of the class described, the parts, being standard, there is no necessity for boring or punching during the assembly of the building. This is also true of all of the studdings and interconnecting braces.
- With regard to the bolt holes, it is pointed out hereinabove, as one object of the invention, to provide connecting means in which the shear stresses are absorbed or carried by the members themselves, and, further, to provide a bolt, the nut of which grips the engaged plate so that the device can be assembled without the use of a tool on the inside of the unit. The structure whereby these objects are attained is best illustrated in Figs. 4 and 5. The reference numerals 14 and 14' indicate the engaging flanges of two channel members 12 and 15. The bolt holes in both of these channel members are punched so as to form interfitting countersunk portions 35 and 35'. Reference numeral 36 indicates the head of a screw bolt 37 which extends through the bolt holes to hold the members in locked engagement. Reference numeral 38 indicates a special form of nut which has an embossed central portion 39 adapted to rest over the countersunk portion of the inner flange and also has projecting pointed corners 40 adapted to engage and grip the inner surface of the engaged flange 75

when the bolt is tightened. Through the use of this construction the bolt may be tightened without using a wrench or other tool on the nut and, after the two members are assembled, the 5 shear stresses are carried by the countersunk portions of the plates instead of the bolt. It will be understood that this type of bolt hole is employed throughout the entire unit, that is, in both the flanges and the web portions of the 10 channels.

It was pointed out in the first part of the specification, as another object of the invention, to provide a novel type of base plate or base board which could be readily removed to provide access 15 to the interior of the wall and pipe or conduit contained therein. Such a base plate is indicated by reference numeral 45 in Fig. 1, and Fig. 3 illustrates a preferred means for mounting the base plate.

20 Referring to Fig. 3, I show an offset or Z plate 46 secured by means of a bolt 47 to a flange 14 of one of the stud channels. This offset or Z plate may extend the full length of that portion of the wall which is to carry a base plate or it may be 25 a short section positioned adjacent the channel. In any event, it is provided with a pair of spaced bolt holes, one of which receives a bolt 48 which engages a threaded opening in an elongated nut member 49. The other bolt hole 50 is opposite a 30 second threaded opening in the nut member 49 and the base plate is provided with bolt holes which are spaced apart so as to fall into alignment with the openings 50. Through this arrangement the base plate member is secured to 35 the wall by means of bolts 51 which extend through the bolt holes 50 into the second threaded opening in the nuts 49. Bolts 52 may also be provided at the lower edge of the base plate, and it will be understood from the construction so far described, that the base plate can be removed simply by removing the bolts 40 51 and 52 and that the holes in the nuts which receive such bolts remain in their proper position by virtue of the bolts 48.

45 It was emphasized as an important feature of this invention that the channel studdings are employed as door and window jambs in the construction of a building wall. When it is desired to use the studding for this purpose I consider it 50 preferable to form the same with flanges which are substantially twice the width of the flanges on the channels which are used merely for the purpose of studding. This facilitates the mounting of the wall and provides additional space for 55 trimming the wall adjacent the window or door opening. It will be understood, of course, that the narrow type of flanged channel may be employed for this purpose but the wider flange has advantages over the narrow flange. This type of construction is clearly illustrated in Fig. 1 where 60 the studding channels 15a and 15b constitute side jambs for a door opening, the head jamb of which is formed by a horizontal brace 16a. The studding channels 15a and 15b are shown as 65 having wide flanges and the horizontal brace 16a is shown as having narrow flanges. It is to be understood, however, in view of the remarks above, that the wide flanged channel may be employed for the horizontal brace 16a. In carrying 70 out this construction the side jambs, or the channel studdings, and the head jamb, or the horizontal brace, are provided with door stop members 53 which may be of any suitable construction, such as inverted channels, such members being secured to the studding and the brace 75

by means of bolts 31a, of the type hereinabove referred to, which extend through the standard bolt openings in the studding and brace members, and are adapted to be engaged by a door 54 (Fig. 14).

The window construction is formed in a manner similar to the door opening and, in this form of my invention, is shown as comprising the studding channels 15c and 15d forming the side jambs of the window and horizontal braces 16b 10 and 16c which form the head jamb and sill of the window. The window frame thus formed is provided with stops or guides, depending upon whether it is a window of the hinged or double hung type. The details in the construction employed in both types of windows will be described later in the specification.

In the construction of a building which is provided with a floor it will be understood that floor joists must be employed and, in this type 20 of construction, the joists, like the other elements, are formed of standard punched channel members, one form of such joist being indicated by reference numeral 55, which is shown as being supported on the sill channel 12. It is to 25 be understood, of course, that any number of such joists may be employed as is common in the building art, also that other types of sections or joist construction may be employed.

It is also a feature of the construction, contemplated by this invention, that all of the channel members are formed with means for supporting a surface or covering material. Such covering material may be either a wall board held in place by reason of retaining strips, a 35 wall board held in place by clips and covered with plaster, or a metal lath covered with plaster. In the event wall board is employed as the covering material, the flanges of the channel members are provided with uniformly spaced 40 slots or openings 56 which are adapted to receive prongs 57 formed on clip members 58 or prongs 57' formed on strip members 59 (see Figs. 16 and 17). The clip members 58 are employed in case the wall board is to be covered 45 with plaster and, as shown in Fig. 16, comprise a flat plate provided with oppositely disposed angle portions 62 and 62' which extend over the edges of adjacent wall board sections 63 and 63'. The prong 57 is of a width corresponding to the 50 width of the slot or opening 56 and is undercut, as indicated at 64, so that the clip, after it is inserted, can be pressed downwardly and locked in place over the lower edge of a slot or opening 56. This same type of prong is employed in 55 connection with the strip 57', the prongs in such case being formed on the web 65 which projects inwardly from an outer strip 66 forming a member which is T-shaped in cross section, the plate 66 having portions which extend over adjacent 60 wall board sections 63a and 63b.

In the regions adjacent the window and door openings the edges of the wall board 63 are covered with trimming strips shown as comprising Z-shaped or offset plates, indicated by reference 65 numeral 68, and secured in place either by means of screws 69 or by prongs similar to those just described in connection with Figs. 16 and 17.

In the event the wall is to be surfaced with a metal lath and plaster, such as is the case with 70 the outer surface of the wall structure shown in Fig. 1, I provide the flanges of the channels with prongs 70 adapted to be received in the lath and bent over the same to hold it in place. The finish strips employed at the openings, in 75

connection with a plaster wall, are mounted on the jamb members before the wall is plastered. A preferred form of such strip is shown in Fig. 15 where the strip 68' is shown as being secured to a jamb or stud channel 15a' by means of a bolt 37a'.

Referring now to Figs. 7 to 9 inclusive, which illustrate the details in the construction of one form of window contemplated by this invention, it will be observed that the horizontal braces 16b and 16c are of the same width as the studding channel 15c which forms one of the side jambs. It is also important in this construction that the studding channels which form the side jambs of the windows be arranged with their web surfaces facing each other, and it is, therefore, necessary to provide some means for supporting the cross braces, or the head jamb and the sill. Such means are shown as comprising angle members or clip members 73 and 74 which are secured to the studding members and the horizontal braces 16b and 16c by means of bolts 75, which extend through the standard openings in the channels forming the studding and braces.

The two side jambs and the head jamb of the window on the inside of the wall are provided with metal trim plates 68 secured to the channel members by means of bolts 69. The sill 16c of the window is of special construction and has a stool 77 on the inside and an offset lip portion 78 formed on the outside providing a weather bar. Reference numeral 79 indicates a backing plate which supports the wall surfacing material 63a, such plate being secured to the sill 16c by means of bolts 79'. Numeral 79a indicates a backing plate for the inner wall surfacing material 63b, such plate comprising an angle which is secured to the sill by bolts 79b. Reference numerals 80, 81 and 82 indicate stop members which are shown as comprising inverted channels secured to the head jamb, the side jambs and the sill plate respectively by means of bolts 83. Numeral 84 indicates a hinged window of the conventional type, supported on the outside of the window sash by means of hinges 85 and 86 and adapted to engage the stop members in the window frame. Reference numeral 87 indicates a resilient weather strip positioned around the outside of the stop members and adapted to be engaged by the stiles and rails of the window. Reference numeral 88 indicates a trim and weather bar which is mounted on the head jamb of the window, and 88' indicates a trim mounted on the outside of the side jamb. Numerals 90 and 91 indicate screens adapted to slide in guide passages 92 and 93, such passages being formed by channel members 94, positioned in spaced relation with the outer edge of the stop members 80, 81 and 82.

In Fig. 10 I show a modified form of construction which is designed for use in walls where a larger portion of the wall is open. This construction is frequently employed in factories and the like and, in the particular type of construction contemplated by this invention, is obtained by forming the studding 100 of two channel members 101 and 101' secured together through their flanges by means of bolts 102. The outer faces of both channel members are provided with stops 103 and 104, respectively, such stops being shown as comprising inverted channels secured to the studding member by means of bolts 105. Reference numerals 106 and 106' indicate the

stiles of windows mounted in the frames formed in this manner.

In Figs. 11 to 13 inclusive I show the manner in which the construction contemplated in this invention may be employed to form a double hung sash window. In this construction the head jamb of the window, indicated by reference numeral 110, which is mounted between the studding members of the frame in the same manner described above, (one of such studding members being indicated at 111) is of special construction in that it is formed with an inverted trough 112. A special clip 114, having a cut out corner 115, is used to support this head jamb or horizontal brace between the two studding members. The side jambs, formed by the studding channels 111 are provided with bent plates 113 and 113', such plates being constructed so as to form guide channels 117 and 118 which receive the stiles 119 and 120 of window sashes 121 and 122 respectively. The bent plates 112 and 113 are secured to the side jambs by means of bolts 124 which extend through the standard openings in the side jambs. Reference numerals 125 and 126 indicate window weights and numeral 127 indicates a division plate for these weights. In this form of my invention the sill plate is also of special construction which, as shown in Fig. 13, is formed with a stool 130, an offset section 131, adapted to be engaged by the bottom rail 121 of the lower window sash, the offset portion 131 terminating in a downwardly inclined portion 132 which is engaged and supported by a special clip member 133 mounted on the studding 111 by means of screws 134 which extend through the standard bolt holes in the studding and the clip. Reference numerals 136, 136a and 136b indicate resilient weather stripping engaged by the rails and stiles of the window sash. These weather strips, which are also contemplated by this invention, are formed of spring bronze, or other suitable resilient metal and provide a window construction which is dust and moisture proof, and reduces infiltration of air to a minimum. Furthermore, the window is easy to operate and will not rattle. The weather strips 136 and 136b in the sill and head jamb, respectively, are held in place by angle members 137 and 137b and bolts 134' and 137c respectively. The weather strips 136a in the side jambs are made U-shaped in cross section and are locked in place by forming them with flanges 138 underlying the offset guide plates 113 and 113'. The side jambs 111 of the windows are provided with sash pulleys and weight pockets (not shown) to facilitate the installation of, and provide ready access to, the weights and sash chains or cables.

In Fig. 18 I show a preferred form of splicing means for use in connection with the channel members contemplated by this invention. Such splicing means comprises a channel plate 140, which fits between the adjacent end portions of two abutting channel members 141 and 141'. Both the flanges and the web portion of the channel plate are provided with pairs of bolt holes 142 which are spaced apart laterally a distance corresponding to the spaces between the sets of bolt holes in the channel members. In this way I provide a splice plate which can be used in conjunction with two channel members regardless of the manner in which they are cut. In the form shown, bolts 143 are mounted in the bolt holes in the flanges of the channels.

In Figs. 19 to 24 inclusive I show a modified form of building construction which may be

made from the channel members of the type described above. This construction is the type ordinarily employed in larger buildings, such as markets, garages, etc., and comprises floor joists 5 150, studding members 151a, floor or ceiling truss 152, the ends of which carry additional studding members 153 which in turn support a roof truss 154. The elements of this construction are, as pointed out above, channel members, similar to 10 those described in connection with Figs. 1 to 18, inclusive, which may be bent or formed to the particular shape necessary to produce the desired structure. The truss 154 is comprised of a top channel 155, bent to form an arch, and a 15 bottom horizontal channel 156. The construction of the end portions of these two channels, whereby they are joined together, is best illustrated in Figs. 20 and 21 where the ends of the 20 channels 155 and 156 are shown as being mounted upon a short channel member 157 and secured thereto by means of bolts 158, the bolt holes being countersunk similar to the bolt holes described hereinabove.

The construction of the struts and braces in 25 the truss 154 is best illustrated in Fig. 22 where the strut 159 is shown as comprising a channel member mounted between the two channels 155 and 156 in normal relation to the bottom channel 156 and secured therein by means of bolts 160, which are received in countersunk bolt holes. The angular brace struts 161 and 161' are channels, similar to the channel 159, which are mounted between the side flanges of the two 30 members 155 and 156, being secured therein by means of the bolts above referred to.

The floor or ceiling truss member 152 comprises two channel beams 163 and 164, spaced apart vertically, the lower beam having its end bent up at an angle and then terminating in a 40 straight portion which is parallel to the end of the upper beam, as indicated at 165, and which is more clearly illustrated in Fig. 23. The ends of these two members are secured together by means of short channel members 167 and 167' and bolts 168. The struts in this truss, like the ones described in the roof truss, comprise vertical channel members 169 and angle channel members 170, such members having their ends received between the flanges of the channel 50 beams 163 and 164 where they are secured by means of bolts 171.

It will be apparent, from the foregoing description, that the building material contemplated by this invention is of a nature such that 55 it can be economically manufactured, since the bolt holes and other openings, together with the lath prongs, can be punched in the flat with a single operation, after which the channel shape can be formed by a rolling or forming step, the 60 entire procedure being a substantially continuous operation. Since the punching of all the channels is standard the builder can furnish the manufacturer with the specifications and the parts can be cut to length after which the 65 building can be assembled by any unskilled workman under the supervision of the builder. The structure has a further advantage in that the sections punched from the large holes can be centrally punched to provide weight sections 70 which can be assembled on a suitable bar to form the window weights.

It is to be understood that, while I have herein

described and illustrated certain preferred forms of my invention, the invention is not limited to the precise construction described herein, but includes within its scope whatever changes fairly come within the spirit of the appended claims. 5

I claim as my invention:

1. A metal building construction embodying: a plurality of vertical and horizontal metal sections interfitted to form a frame, said sections having alined holes at their junction points and 10 interfitting projections on said sections associated with said holes for carrying the shear stresses between adjoining sections; bolts extending through said alined holes; and nuts on the inner ends of said bolts engaging the inner 15 faces of said projections, said nuts having extending corner points adapted to engage and grip the surface of an engaged section.

2. A metal building construction embodying: a plurality of vertical and horizontal metal sections 20 interfitted to form a frame, said sections having alined holes at their junction points and preformed interfitting countersunk portions surrounding said holes for carrying the shear stresses between adjoining sections; bolts extending through said alined holes having screw 25 heads received in said countersunk portions; and nuts on the other ends of said bolts, each of said nuts having a countersunk portion adapted to receive the countersunk portion on an engaged 30 section and extending corner points adapted to engage and grip the surface of an engaged section.

3. For use in a building of the class described, a metal wall frame embodying: a sill member; 35 a plate member; a plurality of studs secured between said sill and said plate, said studs comprising channels the flanges of which are parallel to the two sides of the wall frame formed thereby; a wall coating secured to an inner 40 surface of said frame; an offset plate secured to the flanges on said studs adjacent the lower edge of said wall coating; the offset portion of said plate having apertures arranged in sets therein; nut members mounted on the back of said offset 45 portion behind said sets of apertures, said nut members having two screw holes corresponding with said sets of apertures; a screw extending through one of said apertures in said offset plate into one of said screw holes; a base plate having 50 a portion thereof engaging said offset portion, said base plate having apertures opposite the unoccupied apertures in said offset portion; and screws extending through the apertures in said base plate and said last mentioned apertures 55 in said offset plate into engagement with the other screw hole in said nut.

4. A metal building construction embodying: a plurality of vertical and horizontal metal sections interfitted to form a frame, said sections 60 having alined holes at their junction points and interfitting projections on said sections associated with said holes for carrying the shear stresses between adjoining sections; bolts extending through said alined holes with their threaded 65 ends extending outwardly beyond the exposed faces of said projections; and nuts on said bolts, said nuts having extending corner points adapted to engage and grip the surface of an engaged section adjacent the exposed surface of the cor- 70 responding projection.

WILLIAM C. LEA.
